Primary Examiner — Marissa J Cash*Assistant Examiner* — William B Melliar(74) *Attorney, Agent, or Firm* — Barnes & Thornburg LLP(57) **CLAIM**

I claim the ornamental design for a portable lighting device, as shown and described.

DESCRIPTION

FIG. 1 is a front perspective view of a portable lighting device according to the new design.

FIG. 2 is a left side view of the portable lighting device shown in FIG. 1.

FIG. 3 is a right side view of the portable lighting device shown in FIG. 1.

FIG. 4 is a top view of the portable lighting device shown in FIG. 1.

FIG. 5 is a bottom view of the portable lighting device shown in FIG. 1.

FIG. 6 is a front view of the portable lighting device shown in FIG. 1; and,

FIG. 7 is a rear view of the portable lighting device shown in FIG. 1.

(Continued)

The broken lines shown in the drawings depict portions of the portable lighting device that form no part of the claimed design.

1 Claim, 5 Drawing Sheets
